UNITED STATES PATENT OFFICE

109,207

DESIGN FOR A SELF PROPELLING AIR COMPRESSOR

James H. Cantrell, Jellico, Tenn.

Application January 14, 1938, Serial No. 74,304

Term of patent 3½ years

To all whom it may concern:

Be it known that I, James H. Cantrell, a citizen of the United States, residing at Jellico, in the county of Campbell and State of Tennessee, have invented a new, original, and ornamental Design for a Self Propelling Air Compressor, of which the following is a specification, reference being had to the accompanying drawings, forming part thereof.

Figure 1 is a top plan view of a self propelling air compressor, showing my new design.

Figure 2 is an elevational view, looking at one side of the compressor.

Figure 3 is an elevational view, looking at the other side of the compressor.

Figure 4 is an elevational view, looking at one end of the compressor.

Figure 5 is an elevational view, looking at the other end of the compressor.

I claim:—

The ornamental design for a self propelling air compressor as shown.

JAMES H. CANTRELL,
